HACKSAW

Laird F. Covey, Easton, and George W. Merrow, Bloomfield, Conn., assignors to The Stanley Works, New Britain, Conn.

Filed Aug. 8, 1973, Ser. No. 386,597

Term of patent 14 years

Int. Cl. D8—03

U.S. Cl. D8—96

FIG. 1

FIG. 2

FIG. 3

FIG. 4

FIG. 5

FIG. 6

FIG. 7

FIG. 1 is a perspective view of a hacksaw showing our new design;

FIG. 2 is a side elevational view thereof;

FIG. 3 is an elevational view of the opposite side from that illustrated in FIG. 2;

FIG. 4 is a plan view thereof;

FIG. 5 is a bottom view thereof;

FIG. 6 is an elevational view looking at the handle end thereof; and

FIG. 7 is an elevational view of the opposite end thereof.

We claim:

The ornamental design for a hacksaw, as shown and described.
